UNITED STATES PATENT OFFICE

166,257

GOGGLE FRONT

Arthur Kenyon Jones, Rumford, R. I.

Application January 16, 1952, Serial No. 18,088

Term of patent 7 years

(Cl. D57—1)

To all whom it may concern:

Be it known that I, Arthur Kenyon Jones, a citizen of the United States of America, residing at Rumford, county of Providence, State of Rhode Island, have invented a new, original, and ornamental Design for a Goggle Front, of which the following is a specification, reference being had to the accompanying drawing, forming a part thereof.

Fig. 1 is a front perspective view of a goggle front, showing my new design on a slightly reduced scale in comparison with the disclosures in Figs. 2 and 3.

Fig. 2 is a top plan view;

Fig. 3 is a front elevational view;

Fig. 4 is an edge elevational view; and

Fig. 5 is a section on line 5—5 of Fig. 3.

I claim:

The ornamental design for a goggle front, substantially as shown.

ARTHUR KENYON JONES.
